UNITED STATES PATENT OFFICE.

WALTER J. BRANSON, OF WILKINSBURG, PENNSYLVANIA, ASSIGNEE, BY MESNE ASSIGNMENTS, TO WESTINGHOUSE ELECTRIC & MANUFACTURING COMPANY, OF PITTSBURG, PENNSYLVANIA, A CORPORATION OF PENNSYLVANIA.

CENTRIFUGAL SWITCH.

977,591.

Specification of Letters Patent. Patented Dec. 6, 1910.

Application filed September 8, 1908. Serial No. 452,091.

To all whom it may concern:

Be it known that I, WALTER J. BRANSON, a citizen of the United States, and a resident of Wilkinsburg, in the county of Allegheny and State of Pennsylvania, have invented a new and useful Improvement in Centrifugal Switches, of which the following is a specification.

My invention relates to centrifugal switches such as are commonly employed in connection with single-phase induction motors, and it has for its object to provide a switch of exceptionally simple and economical construction, and by means of which 15 sparking within a motor may be substantially obviated.

Figure 1 of the accompanying drawings is a view, partially in vertical section and partially in side elevation, of a motor embodying the present invention. Fig. 2 is a diagrammatic view of the circuit arrangements of the motor. Fig. 3 is a face view of the rotatable member of the switch, and Fig. 4 is a face view of the stationary member of 25 the switch.

The motor comprises a stationary laminated primary member 1 that is mounted within a casing 2 and is provided, as is usual in single-phase induction motors, with main 30 and auxiliary windings 3 and 4, respectively, and a rotatable secondary member 5, for the shaft 6 of which bearings 7 are provided in the ends of the casing 2. During operation, the main primary winding 3 is maintained 35 in connection with a suitable supply circuit (not shown), while the auxiliary winding 4 is connected to the circuit by means of the centrifugal switch which constitutes the present invention only during, and for the 40 purpose of assisting, the starting of the motor.

The centrifugal switch, just referred to, comprises two continuous rings 8 and 9 which loosely surround the shaft 6, and are 45 of different widths, the inner ring protruding at one end from the outer. Each of the rings 8 and 9 is provided with a pair of radially projecting lugs 10 which are riveted or otherwise suitably secured to an annular 50 insulating ring 11, which, in turn, is secured to the end of the casing 2. The lugs 10 constitute convenient means for connecting the terminals of the auxiliary winding 4 to the rings. The switch comprises, further, an

annular bracket 12 that is riveted or otherwise suitably secured to an annular insulating ring 13, the latter being secured to the end of the rotatable member 5. The bracket 12 is provided with diametrically opposite extensions 14 to which brushes 15 are pivotally secured, and with other diametrically opposite extensions 16, between which and the brushes helical tension springs 17 are interposed for the purpose of normally maintaining the brushes respectively in engagement with the stationary rings.

When the brushes 15 engage the stationary rings 8 and 9, the circuit of the auxiliary winding is complete because the annular bracket 12 electrically connects the brushes 70 together. When, however, the motor attains such predetermined speed that the auxiliary primary winding need no longer be employed, the centrifugal force exerted on account of the rotation of the secondary 75 member 5 causes the brushes 15 to move substantially radially outward and out of engagement with the stationary rings 8 and 9, thus interrupting the circuit of the auxiliary winding. It will be seen that the circuit is interrupted as soon as one of the 80 brushes is moved out of engagement with the corresponding ring, with the result that arcing between the remaining brush and its corresponding ring does not occur, even if 85 the said parts remain in engagement. Because of this action, it is not necessary that the springs 17 be so adjusted as to permit the brushes to move synchronously out of engagement with the rings, as is necessary 90 in many switches heretofore employed.

I claim as my invention:

1. A centrifugal switch comprising stationary concentric terminal cylinders of different lengths, and electrically connected rotatable brushes that are maintained in engagement with the respective cylinders except when rotated at greater than a predetermined speed.

2. A centrifugal switch comprising stationary concentric terminal cylinders of different lengths, and electrically connected rotatable and radially movable brushes that are normally and resiliently maintained in engagement with the respective cylinders.

3. A centrifugal switch comprising stationary concentric terminal cylinders, the inner one of which extends beyond the outer,

- and electrically connected rotatable brushes that are maintained in engagement with the respective cylinders except when rotated at greater than a predetermined speed.
- 5 4. In an induction motor, the combination with relatively rotatable primary and secondary members, main and auxiliary windings for the primary member, stationary concentric rings of different lengths surrounding the shaft of the rotatable member and interposed in the circuit of the auxiliary winding, and electrically connected brushes
- 10

carried by the rotatable member and maintained respectively in engagement with the rings except when the motor attains a predetermined speed. 15

In testimony whereof, I have hereunto subscribed my name this 3rd day of September, 1908.

WALTER J. BRANSON.
